HOLDER FOR SARTORIAL ACCESSORIES

Leslie D. Gensmer, Minneapolis, Minn.

Application July 16, 1957, Serial No. 46,961

Term of patent 7 years

(Cl. D86—10)

Fig. 1 is a front perspective view of a holder for sartorial accessories showing my new design;

Fig. 2 is a vertical sectional view thereof taken on the line 2—2 of Fig. 1; and

Fig. 3 is a top plan view thereof.

The broken line illustration of collar stays and a cuff link shown respectively in Figs. 1 and 2 is for illustrative purposes only.

I claim:

The ornamental design for a holder for sartorial accessories, as shown and described.
